UNITED STATES PATENT OFFICE.

CYRUS L. BUNDY, OF KINGSLAND, NEW JERSEY, ASSIGNOR, BY MESNE ASSIGNMENTS,
TO WILLIAM H. MINER, OF CHICAGO, ILLINOIS.

FRICITION DRAFT-RIGGING FOR RAILWAY-CARS.

1,048,648.

Specification of Letters Patent. Patented Dec. 31, 1912.

Application filed May 28, 1909. Serial No. 498,824.

To all whom it may concern:

Be it known that I, CYRUS L. BUNDY, a citizen of the United States, residing at Kingsland, in the county of Bergen and State of New Jersey, have invented a new and useful Improvement in Friction Draft-Rigging for Railway-Cars, of which the following is a specification.

My invention relates to improvements in friction draft rigging for railway cars.

The object of my invention is to provide a friction draft rigging of a strong, simple, efficient and durable construction which will be short in length and compact in form and occupy a small amount of space under the car, and at the same time will be conveniently accessible and easily put in place on and removed from the car.

To practically accomplish this object or result, and herein my invention consists, I combine with the draw-bar and draft yoke and draft members having front and rear stops or shoulders for the followers to abut against, a pair of wedge faced followers tending through the draft yoke, the front one abutting directly against the rear end of the draw-bar and the rear one abutting directly against the yoke or against the filler block at the rear end of the yoke, if the yoke is curved at its rear end and a filler block employed therein, a pair of upper and lower friction blocks extending through the draft yoke and having inclined or wedging faces in frictional engagement with the inclined or wedge faces of the front and rear followers, the friction blocks having on their upper and lower faces recesses to receive and accommodate the upper and lower members of the draft yoke and permit the friction blocks to move to and from each other under action of the wedge faced followers, a vertically arranged spring and a pair of spring seats or bearing plates and connecting bolts extending between and connecting the lower spring seat with the upper friction block, the upper spring seat or bearing plate bearing against the lower face of the lower friction block. A removable tie plate extends between the draft members or draft sills and supports the rear end of the draft rigging. The filler block at the rear end of the draft yoke is furnished with supporting arms, one fitting on each side of the draft yoke and resting upon the tie plate.

My invention also consists in the novel

construction of parts and devices and in the novel combination of parts and devices herein shown and described and more particularly specified in the claim.

In the drawings, Figure 1 is a side elevation partly in longitudinal section of a friction draft rigging embodying my invention; Fig. 2 is a plan view partly in horizontal section; Fig. 3 is a vertical cross section on line 3-3 of Fig. 1; Fig. 4 is a horizontal section on line 4-4 of Fig. 1; Fig. 5 is a detail perspective view of the lower friction block; Fig. 6 is a detail perspective view of the filler block of the yoke.

In the drawing A represents the center or draft sills of the car to which the draft rigging is applied, A¹ the front sill and A² the carrier iron.

B is the coupler draw-bar, B¹ the draft yoke and B² the filler block at the rear end of the draft yoke, the same being preferably furnished with supporting arms b which rest upon the removable tie plate C and thus support the rear end of the draft rigging.

D D are front and rear draft members secured to the draft sills A in a suitable manner, as by rivets d.

F F are the followers, the front one abutting directly against the rear end of the draw-bar and the rear one abutting directly against the draft yoke or the filler block B² therein, if one is employed. The followers F F have each oppositely inclined or wedging faces f f, the portion of each follower upon which the wedge faces f f are formed, being preferably integral with the portion of the follower which engages the draft members D. The inclines of the front and rear followers face each other; that is to say, the inclines are on the adjacent faces of the followers.

G and G¹ are upper and lower friction blocks extending through the draft yoke B¹ and each having inclined or wedging faces g g engaging the corresponding inclines or wedging faces f of the followers F. The upper friction block G has on its upper face a channel or recess g¹ to receive and accommodate the upper limb or member of the draft yoke and the lower friction block G¹ has a corresponding but deeper recess or channel g² on its lower face to receive and accommodate the lower limb or member of the draft yoke G¹ and thus permit the upper and the lower friction blocks to separate or

move to and from each other as required under action of the opposing wedge faced followers F F.

H h are upright depending springs arranged below and acting at their upper ends against the lower friction block G¹ and at their lower ends against a spring seat or bearing plate H¹ which is connected by a pair of depending rods K with the upper friction block G, an upper spring seat or bearing plate H² being preferably interposed between the upper end of the springs and the lower friction block G¹. The depending connecting rods K extend through the upper and lower friction blocks F F¹ and the upper and lower spring seats or bearing plates H² H¹ at the ends thereof and fit astride the springs. These connecting rods or bolts K are provided with heads K¹ at their upper ends and threaded nuts K² K³ and a cotter K⁴ at their lower ends. As in my invention it is only the wedge faced followers and upper and lower friction blocks which fit within the draft yoke and as the spring is an upright or depending one arranged below the draft yoke, it will be readily seen by those skilled in the art that my improved draft rigging is not only very short and compact but also very accessible and capable of being easily and quickly removed and replaced and also of exceedingly simple construction and capable of being manufactured at small cost. The shortness of my draft rigging adds greatly

to its strength and durability and the draft yoke is further strengthened by the draw-bar followers and filler block, and by reason of the short space between the followers. The upright spring is ordinarily arranged below the draft yoke and friction blocks, as illustrated in the drawing and this is the preferred arrangement.

I claim:—

In a friction draft rigging, in combination; a draw bar; draft yoke; draft members; a pair of wedge faced followers extending transversely through the draft yoke and engaging the draw bar and draft yoke; upper and lower friction blocks extending transversely through the draft yoke and having inclined friction faces cooperating with the inclined faces of the wedges; a vertically arranged spring acting at its inner end against one of said friction blocks; connecting rods extending through said friction blocks and located on opposite sides of the draft yoke; and a spring seat connected to said rods for the outer end of the spring to bear against, said rods removably connecting said blocks together, and the rods, friction blocks and spring seat removably encircling one arm of the yoke, substantially as specified.

CYRUS. L. BUNDY.
